DOORPOST FOR RAILWAY CARS

William F. Kiesel, Jr., Hollidaysburg, Pa.

Application December 24, 1931
Serial No. 583,011

13 Claims. (Cl. 189—46)

This invention relates to door posts for railway cars and more particularly to side door posts for box cars or the like.

Heretofore it has been customary to make a box car door post of built-up construction—for example, of several pieces of steel, at times, including wooden members. With such door post constructions, especially those involving a wooden nailng piece, difficulty has been experienced in the trucking of freight into and out of the car, the posts being frequently damaged by the impact of trucks or their lading; and the use of rolled steel post members has limited the value of the door posts as strengthening parts joining the top and bottom chord of the side truss of the car.

The object of the present invention is to eliminate the foregoing difficulties by the provision of a one-piece door post, preferably made of cast metal, including various formations facilitating the attachment of the post to frame members of the car and other structural features of advantage which are hereinafter more specifically described.

One form or example of a door post of my invention is illustrated in the accompanying drawings, whereof:

Fig. I represents a fragmentary view, in side elevation of a box car, designed as a carrier for automobiles and embodying side door posts of my invention.

Fig. II represents an enlarged vertical cross section of the same, taken as indicated by the lines II—II of Fig. I.

Fig. III represents an enlarged horizontal cross-section of the same, taken as indicated by the lines III—III of Fig. I.

Fig. IV represents a side elevation of the right hand door post of Fig. I.

Fig. V represents a fragmentary perspective view of the right hand door post of Fig. I.

Fig. VI represents a plan view of the same; and,

Fig. VII represents a cross section of the door post, taken as indicated by the lines VII—VII of Figs. I and IV.

With reference to the drawings, there is shown a portion of a box car, which in general is of ordinary construction and which is designed particularly for carrying automobiles. The side wall of the car is generally designated by the numeral 1 and has therein a door opening defined at its sides by door posts 2. In the example selected for illustration the door opening is closed by double sliding side doors of the bottom-hung type, one

of which is designated at 3a and the other at 3b. The particular construction of the double doors 3a and 3b is not here described in detail, for it will be recognized that such doors are of a well-known type used with automobile cars. The wooden floor of the car is designated at 4 and is shown supported upon a channel sill 5.

To the channel sill 5 brackets 6 are riveted at spaced intervals, the brackets 6 supporting a track 7. Each door 3a, 3b is provided near its bottom edge with housings 8, accommodating roller bearing rollers 9 which engage the track 7, and with suitable guide pieces 10 and 11 for keeping the door on the track. The doors 3a, 3b are corrugated for stiffening purposes with horizontal corrugations 12 and vertical corrugations 13. To clear the door opening to the maximum width, both doors 3a and 3b are slid in an obvious manner in opposite directions along the tracks 7 at the side wall of the car.

At the top of the door opening, as clearly shown in Fig. II, there is a side plate 14 of customary Z-bar form having an upturned flange 15 which abuts against and is secured at its inside to a depending flat plate 16. The web portion 17 of the Z-bar side plate 14 is disposed horizontally. To the outside of the downturned flange 18 of the Z-bar side plate 14 there is riveted a hood 19 which projects outwardly and downwardly. The hood 19 is provided with an extension 20 projecting around the top edges of the doors 3a, 3b. The hood 19 and its extension 20 are also in the form of Z-bars. At the inside of the down-turned flange 18 of the side plate 14, there is secured by rivets a J-bar weather strip 21 affording a trough or gutter 22 which, when the doors are closed, extends horizontally along the inside top edges of the doors 3a, 3b beneath extension plates 23 in the form of angles at the top edges. Each door 3a, 3b is provided at its outside top corner with a retainer plate 24. The arrangement of the J-bar weather strip 21 and the neighboring parts is more fully described in the pending application for U. S. Letters Patent, Serial No. 571-310, filed October 27, 1931, of Joel Hubert Mattern, and forms no part of the present invention.

While the side plate 14 and the flat plate 16 to which the side plate is attached extend longitudinally of the car well beyond the confines of the door opening at each side thereof, the J-bar weather strip 21 is substantially commensurate in length with the width of the door opening.

As thus far described, the construction of the side doors and of the car frame at the side door opening is merely typical of an example of a box

car construction to which the hereinafter described door posts of my invention are especially adapted.

Each door post 2, as clearly shown in the cross-sectional view of Fig. III and the perspective view of Fig. V, has a main jamb section of hollow form and of substantially triangular cross-section. The outer flat face of each post is designated at 25; the rear face which forms a right angle therewith is designated at 26, and the inner face which is presented to the door opening and which slopes with a gradual curve from the vertical plane of the outer face 25 inwardly and longitudinally toward the corresponding car and is 10 designated at 27. Each side door post 2 is preferably made of cast metal and has integral therewith various formations, including anchoring sections at each end, adapted for attachment to the car frame at the door opening as will be more 15 fully explained.

In Fig. V there is shown a perspective view of the right hand door post 2, and it will be apparent that the left hand door post 2 is of reverse form. In the case of each door post, the main 25 jamb section, which is of substantially triangular form, merges at the upper end of the post with a rhomboidal section which is adapted to fit between the side plate 14 and the depending flat plate 16. This formation affords a top face 28 30 which abuts against the underside of the horizontal web 17 of the side plate 14. It also affords at the outside means for direct attachment to the downturned flange 18 of the side plate 14 and to the flat plate 16, the same comprising vertical webs 29 and 30, respectively. The vertical webs 29 and 30 are provided with apertures 31 in which the securing rivets are inserted.

At the lower end of each door post 2 there is formed integrally with the post proper horizontal base flanges 32, and a vertical base flange 33, these flanges having apertures 34 for the reception of rivets. The vertical base flange 33 extends downwardly at the outside of the channel sill 5 and abuts against and is directly attached to the vertical surface 35 of the latter element. The horizontal base flanges 32 of the door post 2 rest upon the upper horizontal surface 36 of the underlying channel sill 5 and are riveted thereto.

Extending lengthwise of each door post 2, there 50 is formed integrally with the post proper a flat flange 37. The vertically disposed flat flange 37 projects rearwardly from the rear edge of the jamb section in the plane of the outer face 25 of the post. This flange 37 is also provided with a 55 series of apertures 38 for the insertion of bolts and rivets, by which the flange is directly secured to the side sheathing 39 of the car. In the right angle formed between the flange 37 and the rear face 26 of the door post, a wooden 60 frame post 40 may be accommodated, as shown in Fig. III. The wooden post 40 is preferably recessed at 41 to receive the heads of bolts and rivets.

On the outer face 25 of each door post 2, there 65 is formed near the inner edge a weather sealing section or flange 42, this part being bent to form a hook, as shown in Fig. III. The weather sealing flange 42 extends vertically from a point near the upper end of the post, just beneath the trough or 70 gutter 22 of the J-bar 21, to a point near the lower end of the post where the flange is cut away as indicated at 43. The cut away portion 43 follows substantially the contour of the protective covering 44 at the outside edge of the wooden 75 floor 4 of the car. When the doors are closed, as

shown in Fig. III, the hook-shaped flange 42 of each door post is engaged by a clip or sealing strip 45 attached to the side edge of the door and adapted to interlock with the flange on the door post. Each clip or weather sealing strip 45 may also have associated therewith an angle 46 at the edge of the door. In an obvious manner the engagement between the clip or weather sealing strip 45 and the hook-shaped flange 42 effects a tight seal at the side edges of the doors when the latter are closed, preventing rain or snow from beating in at these areas. It will be observed that the longitudinally extending flange 37 at the rear edge of each door post 2 is so spaced from the hook shaped weather sealing flange 42 that free access may be had to the rivets or bolts, which comprise the means for attaching the sheathing 39 to the door posts, when the doors are in closed position.

For the purpose of lightening the door posts 2, without detracting from their strength as truss members joining the top and bottom chords of the side frames of the car, a series of rectangular openings 47 are provided in the rear face 26 of each post.

From the foregoing description it will be apparent that the sloping inner faces 27 of the door posts 2 permit greater freedom of movement for the trucking of freight into and out of the car, especially when the trucks enter or leave obliquely with relation to the platform alongside the car. Furthermore, no sharp edges are presented at the inside of the door openings, to be damaged by the movement of freight into and out of the car. It will also be apparent that while the door posts 2 are hollow, and hence of relatively light and inexpensive construction, they serve as rigid members joining the top and bottom chord of the side frame or truss of the car. The various flanges and other formations which are directly attachable to the side plate 14, the side sill 15, and the side sheathing 39, are all formed integrally with the post proper and hence facilitate the assembly of the car frame.

While I have described one particular example of the embodiment of my invention in a railway car, it will be readily apparent that various changes may be made in the form of the door posts specifically illustrated and referred to herein without departing from the spirit of my invention as defined in the appended claims.

Having thus described my invention, I claim:

1. In a railway car having a side door opening, side plate and side sill, a cast metal side post for said opening, said post having a jamb section and having anchoring sections at the top and bottom thereof adapted for direct attachment to said side plate and sill respectively, and an outer vertically extending weather sealing section adapted to cooperate with a door sealing element, said attaching and sealing sections being all formed integrally with the post proper.

2. In a railway car having a side door opening, a Z-bar side plate, a depending inner plate secured thereto, and a side sill, a side post for said opening, said post having the upper end thereof formed with sections directly attachable to the side plate and said depending plate, said post having also an integrally formed weather seal flange and a base directly attachable to the side sill.

3. In a railway car having a side door opening, and a Z-bar side plate above said opening, a depending plate secured to the inside of said side plate, and a cast metal side post having its upper end fitting between said side plate and said depending plate and having an integrally formed weather seal flange.

4. In a railway car having a side door opening, a side plate, and a side sill affording horizontal and vertical surfaces, a side post for said opening, said post having means at the top thereof for direct attachment to the side plate, an integral weather seal section extending lengthwise thereof, and integral horizontal and vertical flanges at the bottom thereof directly attachable to the horizontal and vertical surfaces of the side sill. 80
- 10 5. In a railway car having a side door opening, and a side sill beneath said opening affording horizontal and vertical surfaces, a cast metal side post having integral therewith horizontal and vertical base flanges adapted for attachment respectively to said horizontal and vertical surfaces of the side sill, and an outer weather sealing section extending lengthwise of the post. 85
- 15 6. In a railway car having a side door opening, hollow cast metal door posts defining the sides of said opening, the vertically extending faces of said posts adjacent to the door opening sloping from the outside vertical planes of the posts inwardly and longitudinally toward the adjacent car ends and presenting a smooth surface to the 90 door opening. 95
- 20 7. In a railway car having a side door opening defined, in part, by side door posts, the vertically extending faces of said posts presented to the door opening each sloping from the outside vertical planes of the posts inwardly and longitudinally toward the corresponding adjacent car ends, each of said posts being provided on the outer side thereof with an integrally formed, longitudinally extending weather-sealing flange. 100
- 25 8. In a railway car having a side door opening, and a side post therefor having a vertically extending weather sealing flange on its outer face adjacent its inner edge, a door with a sealing strip at its side edge adapted to cooperate with said flange, said post having integral therewith an additional flange projecting from the outside rear edge longitudinally of the car for attachment to the side wall sheathing and so spaced from the weather sealing flange that free access may be had to the sheathing attachment when the door is in closed position. 105
- 30 9. In a railway car having a side door opening, 110
- 35 10. As an article of manufacture, a cast side door post having a jamb section proper, a weather sealing section adapted to cooperate with a door sealing element, and anchoring sections at each end thereof all formed integrally. 90
- 40 11. As an article of manufacture, a cast steel side door post for a railway car, said post having a jamb section proper, a weather sealing flange extending vertically along the outer face thereof, attaching flanges at each end thereof, and a vertically disposed flange extending rearwardly from the rear edge of the jamb section proper, all of said flanges and sections being integrally formed. 95
- 45 12. As an article of manufacture, a cast metal side door post for a railway car side door opening, said post having a main jamb section proper of hollow form, flanges at the top and bottom thereof for attachment to a side plate and side sill respectively, and a weather sealing flange extending longitudinally of the jamb section proper on the outer face thereof, all of said flanges being formed integrally with the jamb section. 100
- 50 13. In a railway car having a side door opening defined, in part, by hollow metal side door posts, the vertically extending faces of said posts adjacent to the door opening each sloping from the outside vertical planes of the posts inwardly and longitudinally toward the corresponding car ends and presenting a smooth surface to the door 115 opening, said post having an integrally formed flange extending toward the corresponding end of the car in substantially the outer plane of the post and to which is adapted to be secured the side wall sheathing of the car. 120
